UNITED STATES PATENT OFFICE

100,993

DESIGN FOR A COVER FOR A COOKING PAN OR THE LIKE

Joseph W. Fay, Villa Park, Ill., assignor of one-half to Ersyl F. Chambliss, Chicago, Ill.

Application November 18, 1935, Serial No. 59,637

Term of patent 3½ years

To all whom it may concern:

Be it known that I, Joseph W. Fay, a citizen of the United States, residing at Villa Park, in the county of DuPage and State of Illinois, have invented a certain new, original, and ornamental Design for a Cover for a Cooking Pan or the Like, of which the following is a specification, reference being had to the accompanying drawing, forming a part thereof.

Figure 1 is a top plan view of the cover showing my design; and

Figure 2 is a sectional view through a portion of the cover showing the side of the handle in elevation.

The dominant feature of my design resides in the provision of two circular depressions in tangential relation in the surface of the cover, with the handle portion extending normal to a line drawn through the centers of said depressions across the point of tangency of said depressions.

I claim:

The ornamental design for a cover for a cooking pan or the like, as shown and described.

In witness whereof, I hereunto subscribe my name this 15th day of November, 1935.

JOSEPH W. FAY.
